UNITED STATES PATENT OFFICE

SANDOR ROSENBERG, OF NEW YORK, AND JACOB HOCHMAN, OF BROOKLYN, NEW YORK

FLYING MACHINE

Application filed February 25, 1930. Serial No. 431,247.

This invention relates to flying machines and the improvements are directed to a novel form of helicopter, embodying means whereby the machine may rise and descend in a substantially vertical plane.

As will presently appear it is proposed to provide means, conveniently termed a condenser or compressor, adapted to be rotated and to condense or compress the air passing therethrough and to discharge said compressed air onto a blade positioned rearwardly thereof to facilitate the rise of the machine and to retard the descent thereof, both rise and descent taking place in a substantially vertical plane.

Another object of the invention is to provide means for carrying a plurality of condensers or compressors, said means embodying a single casting and being adapted to also support a plurality of blades, disposed between and parallel with the horizontal axes of said condensers.

Still another object is to provide supporting means adapted to be carried by the fuselage of a flying machine, said means embracing a rotatable element affixed to said means for carrying said condensers.

A further object of the invention resides in the production of a novel form of condenser or compressor having a forward edge greater in width than the retreating edge thereof; and further having a forward edge greater in length than the retreating edge thereof, said dimensional arrangements tending to condense or compress the air passing through the condenser or compressor in order that the compressed air may be discharged with great velocity from said retreating edge.

A still further object is to provide novel means whereby the width of the retreating edge of a condenser may be varied with respect to the width of the forward or leading edge of a condenser.

With these objects in view, together with others which will appear as the description

proceeds, the invention resides in the novel formation, combination and arrangement of parts, all as will be described more fully hereinafter, illustrated in the drawings, and particularly pointed out in the claims.

50

In said drawings:

Figure 1 is a central vertical sectional view of the means carrying the series of condensers, and also of the supporting means for the first-named means, the condensers being shown in elevation.

Fig. 2 is a horizontal sectional view taken on the line 2—2 of Fig. 1, the condensers and intervening blades being shown in plan.

Fig. 3 is a plan view, slightly enlarged, of the means carrying the series of condensers and blades.

Fig. 4 is an elevation thereof.

Fig. 5 is a detail view, in plan, of the base member showing the ball race for the bearings.

Fig. 6 is an inverted plan view of the flanged coupling, also illustrating a portion of the ball race.

Fig. 7 is a sectional view of a condenser and a companion blade, illustrating diagrammatically the course of air currents through the former and their impingement on the latter in a compressed or condensed condition.

75

Fig. 8 is an elevation of a flying machine with our invention applied thereto.

Fig. 9 is a view like unto Fig. 2, but showing a modified form of condenser.

Fig. 10 is a sectional view taken on the line 10—10 of Fig. 9.

Referring now more in detail to the accompanying drawings wherein like characters of reference denote similar parts throughout the several views, let 11 indicate generally a flying machine having the usual propeller 12 and the fuselage 13, the latter being adapted to support our invention, as will presently appear. It will, of course, be understood that the showing of the flying

85

90

machine in Fig. 8 is illustrative, rather than restrictive, as obvious the particular form of flying machine does not per se limit the application of our invention.

As previously pointed out it is proposed to provide a combination of parts whereby the flying machine will rise, with its burden, vertically in its ascent and descend to the earth vertically and landing thereon without a shock of importance enough to notice, the aforesaid actions operating somewhat in the nature of an auger entering wood.

To this end we propose to provide a plurality of compressors or condensers 14, each having an open front and rear, as shown, a flat bottom 15, sides 16 and a top portion 17. Upon inspection of Figs. 1 and 2, it will be observed that the sides 16 converge from the forward edge to the retreating edge of the condenser, and further that the top portion 17 slopes downwardly from the forward edge to the retreating edge, this arrangement producing a structure wherein the width and length of the forward edge is greater than the retreating edge as to width and length. In short, each condenser presents an open front of a greater area than its open rear. As shown in Fig. 2, we provide four of these condensers, though, of course, no restriction as to number is contemplated, and between each pair of condensers we position a plurality of blades which are inclined at an acute angle to the horizontal plane of said condensers, the leading edge of the blades being adjacent the retreating edge of said condensers.

The means for carrying said condensers 14 and blades 18 comprises the element 19, shown in Figs. 3 and 4, and embodies a plurality of outwardly directed flanges 20, to each of which a condenser is secured by means of fasteners 21, (see Fig. 2). Said element 19 is further provided with spaced lugs 22 for the reception of the end portions 23 of said blades, suitable fasteners 24 being used for this purpose, as clearly shown in said Fig. 2. As shown in Fig. 1, the bore 25, in said element 19, receives a sleeve 26, the latter fitting around shaft 27, the latter, the sleeve 26 and the element 19 being bound together by means of a pin 28, or the like. The lower portion of said shaft 27 is reduced in diameter, as shown at 29, for the reception of a coupling 30 and a base member 31, the latter being suitably affixed to the fuselage 13 of a flying machine. As shown in Fig. 1, the end of the shaft portion 29 carries a bevel gear 32 meshing with a similar gear 33, affixed to shaft 34 extending from any convenient source of power, (not shown). Obviously, the rotation of said shaft 27 and the parts carried thereby, is imparted from said shaft 34, and in order to reduce friction to a minimum we propose to provide a thrust collar 35 which is interposed between the fuselage 13 and the gear 32, and further it

will be noted upon inspection of Figs. 5 and 6, that said base member 31 is provided with a ball race 36 which cooperates with a ball race 37 in said coupling 30 to define a continuous groove for the reception of ball bearings 38. Said coupling 30 is affixed to the shaft portion 29, by means of screws 39, or the like, and naturally rotates with the shaft together with the parts just described. 70

As shown in Fig. 1, said sleeve 26 also supports a propeller arrangement 40, which includes a suitable casting 41, having a knob portion 42 at one end and a threaded stud 43 at its other end, the latter being provided with left-hand threads and adapted to threadedly engage the upper portion of said sleeve 26 as shown. In view of this arrangement it is obvious that the propeller 40 rotates with the shaft 27. 75 30

After the flying machine has been equipped with our invention and it is desired to ascend, the usual motor, with which the machine is equipped, is started, the power being transmitted to the shaft 27 and its connected parts, through the bevel gearing 32—33 and shaft 34, all parts rotating simultaneously. When a minimum number of rotations has reached a speed of 100 revolutions per minute terrific high-velocity air currents pass through the rotating condensers and in view of the converging outlet, of said condensers, as pointed out hereinbefore, materially increases the velocity of said air currents which pass uninterruptedly through said condensers and impinge against the inclined blades 18 and as the increased velocity constantly supplied a continuous solid air force, the machine rises upwardly. Hence the chief lifting power is to be considered primarily as present in the plane and secondly, by the converging top portion of said condensers. Obviously, as the speed of rotation of the condensers increases a like increase takes place in the velocity of air passing through said condensers. When the machine descends under the law of gravitation, its drop is retarded by regulating the rotation of the condensers, which will permit said machine to descend so gradually and lightly as not to cause a single shock to its occupants.

An inspection of Fig. 7 will instantly reveal the actions hereinbefore described in detail. It will also become apparent that the converging or sloping top portions of the condensers have a certain lifting power in themselves as they cut through the air in operation and offer but a very little resistance to the air when in operation. As the length and width at the leading edge of the condensers is greater than the length and width at the retreating or rear edge, it follows that as the condensers cut through the air a great volume of air is added and when said air is condensed into a lesser space, due to the aforesaid convergence, air currents of

great force leave the retreating edge of the condensers and impact the blades 18 which are pitched at an angle to cause a lifting action in said machine.

- 5 As shown in Figs. 9 and 10, the condensers 14 may be made box-like in formation, hinged vanes 44 being internally arranged adjacent the sides of said condensers as shown. These vanes may be swung outwardly to the positions, indicated and locked in that position by means of pins 45 arranged in one of the apertures 46. This arrangement permits a certain amount of adjustment to regulate the quantity of air passing through the condensers. In this instance, and in our preferred form, the condensers rotate in the direction of the full-line arrows, while the discharged air moves in the direction of the dot-and-dash arrows.
- 10 While the present is a disclosure of the preferred embodiments of the invention, it is to be understood that the same is not limited thereto, as various changes in the minor details of construction, proportion and arrangement of parts may be resorted to without departing from the spirit of the invention as defined in the appended claims.

We claim:

1. In a flying machine, the combination with supporting means, a rotatable shaft, a plurality of box-like compressors adapted to compress air as the same are rotated, and a plurality of angularly arranged blades disposed parallel with the horizontal plane of said compressors and arranged to receive the air discharged from said compressors.
2. In a flying machine, the combination with supporting means, a rotatable shaft, a plurality of box-like compressors adapted to compress air as the same are rotated, each of said compressors having a forward edge of a width greater than the retreating edge and a plurality of angularly disposed blades arranged between said compressors and adapted to receive the compressed air discharged from said compressors.
3. In a flying machine, the combination with supporting means, a rotatable shaft, a plurality of box-like compressors adapted to compress air as the same are rotated, each of said compressors having a forward edge of a width and length greater than the retreating edge thereof and a series of angularly disposed blades arranged behind the retreating edge of an adjacent compressor and adapted to receive the compressed air discharged therefrom.
4. In a flying machine, the combination with supporting means, a rotatable shaft, a plurality of box-like compressors adapted to compress air as the same are rotated, means for regulating the degree of compression of the air and a series of angularly disposed blades arranged parallel with the horizontal

plane of said compressors and adapted to receive the air discharged therefrom.

5. A device of the character described comprising a rotatable support, a box-like compressor borne by said support, said compressor having a forward edge of greater width than the retreating edge and an angularly disposed blade positioned behind said retreating edge. 70

6. A device of the character described comprising a rotatable support, a box-like compressor borne by said support, said compressor having a forward edge of greater width and length than the retreating edge and an angularly disposed blade positioned behind said retreating edge. 75

7. A device of the character described comprising a rotatable support, means for compressing air currents and borne by said support, said means including a series of box-like compressors having a forward edge of greater width than the retreating edge thereof and a plurality of angularly arranged blades disposed between said compressors and adapted to receive the discharged currents of air from said compressors. 80

8. In a device of the character described, the combination with a rotatable support, of a series of box-like compressors borne by said support, each of said compressors having a forward edge of greater width and length than the retreating edge thereof and a plurality of angularly arranged blades disposed between said compressors and adapted to receive the discharged compressed currents of air from said compressors. 90

In testimony whereof we affix our signatures.
